ANTI-RESTRIKING OIL CIRCUIT BREAKER HAVING AN ANTI-CAVITATION DEVICE
Adrien W. Roth, Aarau, Switzerland, and Albert Catella and Gilbert Nicoud, Lyon, France, assignors to Compagnie Generale d'Electricite, Paris, France, a corporation of France

Filed June 15, 1961, Ser. No. 117,363
Claims priority, application France, June 21, 1960,
830,668
21 Claims. (Cl. 200—150)

The present invention relates to a circuit breaker and more particularly to a high-voltage, small oil-volume circuit breaker provided with anti-restriking means and with a control mechanism controlling the opening speed of the circuit breaker to permit proper operation thereof irrespective of the nature of the overload causing actuation of the circuit breaker.

It has been frequently proposed, for purposes of suppressing the restrikings after the interruption of capacitive currents by means of the circuit breakers having a small volume of oil, to blow oil into the space in which the arc is produced, in order to accelerate the regeneration of the dielectric strength between the contacts after a natural passage of the current through zero. Such forced blowing or blast has as its effect to chase the ionized material out of the space between the contacts and to replace the same by non-ionized material.

It is also known that if, within the first half-period which follows the separation of the contacts of the circuit breaker, the opening distance attains a sufficient value, then the interruption without restriking finds itself favored; to obtain such result it has been customary in the prior art either to break up the circuit breaker into a great number of interrupting chambers or to impart to the movable rod of each interrupting chamber a very high speed from the moment of separation of the contacts and consequently to impart thereto a very high acceleration, prior to the separation. In the presence of the complication and difficulties of realization which seem to result therefrom, it has always been recommended to date to seek the interruption without re-striking by means of a powerful forced blast, whereas a slight augmentation in the rapidity of increase of the opening interval has been indicated only as auxiliary means to favor the dielectric regeneration.

However, the forced blast, in addition to requiring the use of relatively powerful pumps and leading to a rather complicated installation, presents the inconvenience of increasing the over-voltages or voltage surges with the interruption of small inductive currents; in effect, in the case of small inductive currents, and contrary to that which takes place in the case of capacitive currents, the voltage surges are caused by the brutal cancellation or draw-out of the current prior to its natural passage through zero, and the forced blast multiplies, to a very high proportion, the current draw-out capacity by the circuit breaker; the forced blast, therefore, finds itself at the origin of voltage surges of which the amplitude can be reduced only by the use of auxiliary damping resistances. These auxiliary resistances and the auxiliary interrupters which such prior art circuit breakers necessitate, complicate the construction and the operation thereof so that an effort is made with conventional circuit breakers including such auxiliary devices to limit the use thereof to very special cases in which the structure of the network renders the same indispensable. However, as a general rule, the adoption of the forced blast, therefore, entrains very definitely a significant complication with respect to the conventional circuit breaker.

2

Consequently, according to the prior art teachings, there existed a dilemma confronting the designer of circuit breakers, namely either renounce the suppression of restrikings in the interruption of capacitive currents, or employ the forced blast with its inevitable accompaniment of complications.

To escape from this dilemma, the present invention, avoiding recourse to the forced blast, has turned to opening speeds much higher than those realized to date and 10 proposes means to obtain this high speed while at the same time avoiding the inconveniences which could result from this high speed such as causing a phenomenon of cavitation behind the movable contact.

The present invention has as its object a high voltage 15 circuit breaker with a small oil volume in which, in the position of closure, the rod of the movable contact and the fixed contact fingers are disposed on the inside of an oil-injection pot closed by a spark-arrester cover characterized in that, toward the end of closure of the circuit breaker, the rod of the movable contact has its movement damped by the arming force which it exerts on an energy accumulator or energy storage device, which at the beginning of opening imparts a very high speed to the 20 movable contact and injects over the same a current of anti-cavitation oil during the entire duration of possible restrikings in case of capacitive interruption.

Accordingly, it is an object of the present invention to provide a circuit breaker of the type mentioned hereinabove which effectively eliminates the drawbacks and 30 shortcomings of the prior art construction in a simple and effective manner.

It is another object of the present invention to provide a circuit breaker of the type mentioned hereinabove which is reliable in operation with all types of overloads, 35 i.e., which is operative to interrupt capacitive currents as well as small inductive currents.

Still another object of the present invention resides in the provision of a circuit breaker of universal applicability insofar as the interrupted current is concerned which is relatively inexpensive and which achieves such versatility by simple and inexpensive means.

Still a further object of the present invention resides in the provision of a circuit breaker utilizing a high opening speed to achieve the purposes and functions described 45 hereinabove.

Another object of the present invention resides in the provision of a circuit breaker of the type mentioned hereinabove which utilizes a cavitation-compensating means to compensate for the cavitation effects produced by the high opening speeds used in the circuit breaker without the disadvantages normally encountered with oil blasts or the like.

A further object of the present invention resides in the provision of a circuit breaker which obviates the need for 55 forced blasts to regenerate the dielectric strength in the space behind the contact.

Still a further object of the present invention resides in the provision of a circuit breaker operative to interrupt not only capacitive currents but also small inductive currents without the side effects of voltage surges and without the need of auxiliary damping resistances.

Still another object of the present invention resides in the provision of a circuit breaker operative to effectively 65 interrupt, not only short circuit currents and capacitive currents, but also small indicative currents without the necessity of complicated constructional details and complex operational aspects.

These and further objects, features and advantages of 70 the present invention will become more obvious from the following description when taken in connection with the accompanying drawing which shows, for purposes of

illustration only, one embodiment in accordance with the present invention, and wherein

FIGURE 1 is an elevational cross sectional view through an anticavitation device in accordance with the present invention mounted on the fixed contact structure of the circuit breaker.

FIGURE 2 is a cross sectional view taken along line II-II of FIGURE 1, and

FIGURE 3 is a schematic diagram of a circuit breaker and control mechanism according to the present invention provided with means necessary to produce, at the opportune moment, a slow down of the opening speed of the rod of the movable contact.

FIG. 4 is a diagram showing contact movement plotted against time.

FIG. 5 is an illustration of a conventional circuit breaker arrangement having a plurality of interrupting chambers connected in series.

From what will follow hereinafter, the term "opening speed" is to be interpreted as the product of the speed of the rod of the interrupting chamber by the number of interrupting chambers, it being understood that the present invention relates to circuit breakers with a very high opening speed regardless of whether this opening high speed is obtained only by the increase of speed of the rod or also by that of the number of interruptions.

The displacement at high speed of the contact rod within the oil produces a cavitation behind the contact that is within the space ionized by the arc; however, the empty space is a bad dielectric and there is need to compensate for this cavitation by a supply of oil in such a manner that at each instant, in spite of the speed, the state of the space between the contacts is substantially the same as if the speed were zero. It is in that connection that intervenes the anti-cavitation device provided by the present invention. The anti-cavitation device which causes the oil to penetrate through orifices into the space subjected to cavitation is regulated in such a manner as to compensate essentially for this cavitation without producing eddying or swirls; such eddying or swirls would constitute in effect a forced blast which is the source of the shortcomings mentioned hereinabove. The anti-cavitation device provided by the present invention, additionally, offers certain advantages which will result from the description that will follow.

The high speed of the rod is also favorable to the interruption of a short-circuit currents. Referring to FIGURE 4, this figure represents a diagram in which time is plotted along the abscissa and the distances of travel of the movable contact member 12 are plotted along the ordinate.

In FIGURE 4, the curve *a* represents the diagram of the time to the frequency of the network into which the circuit breaker is installed.

Line *b* intersecting the curve 1 at point M represents the position of a movable contact member 12 in the position illustrated in FIGURE 1 in which it abuts against the tubular member 2.

Line *c* intersecting the curve 1 at point N indicates the distance traversed and time elapsed from the position of movable contact 12 in the armed condition of the circuit breaker to the instance when the contacts 12, 1 of the circuit breaker separate.

Line *d* indicates the position of the movable contact 12 for which the interruption of the capacitive current is terminated with certainty, the movable contact 12 having traversed a distance d_0 from the position N at the moment of separation of the movable and fixed contacts 12, 1.

Line *e* which intersects the curve 1 in point O corresponds to the position of the movable contact 12 for which the interruption of the short-circuit current becomes possible, the movable contact 12 having traversed a distance d_1 for the moment of separation of the contacts 12, 1 represented by line *c*, with a lapsed of time equal to t_0 .

Line *f* which intersects curve 1 in point P corresponds to the position normally attained by the movable part 12 a period of the frequency cycle after it has attained the position d_1 , the distance traversed by the movable contact 12 since the separation of the contacts 12, 1 now amounting to d_2 and the time elapsed being equal to t_1 .

The time t_1 corresponds to a passage through zero of the current of interruption—different from the curve *a* which does not represent the current of interruption but only a time diagram independent of the current of interruption—which takes passage through zero place between the positions d_1 and d_2 .

The movable contact 12, reaching the distance d_1 at time t_0 , is represented by the point O. However, the interruption of the current would be effectively produced only at the time of either the first or the second passage of the current through zero after the time t_0 . If T is the period of the alternating current, such passage through zero will necessarily occur at a moment t_1 comprised between t_0 and t_0+T , T being equal to 0.02 second in the case of a fifty cycles per second alternating current and 0.0167 second in the case of a sixty cycles per second alternating current. If V is the speed of the movable contact 12, the position of the movable contact 25 at the moment of the interruption of the current will be comprised between the representative points O and P, the latter corresponding to a distance equal $d_2=d_1+T \cdot V$ from the position of the separation of the contacts 1, 12 at point N corresponding to line *c*.

If the speed of the movable contact 12 is, as presupposed, very high, then the distance d_2 is much greater than d_1 whereby the energy realized by the arc in the course of the interruption at the distance d_2 may be very high, the energy related by the arc in the course of the interruption at the distance d_2 may be very great which renders more difficult the construction of the circuit breaker. However, the circuit breaker according to the present invention does not entail this inconvenience, for it is actuated in such a manner that the speed of the rod, very high at the moment of the separation of the contacts, is brought back to a value much smaller prior to attaining the distance d_1 .

In accordance to one embodiment of the present invention, the slow-down or deceleration mechanism of the rod is actuated in a manner so as to act only in case of a short-circuit interruption, and in these cases it may from the beginning of the movement of the rod, limit the speed to a maximum desired value; it has to be simply controlled by a current measuring device within the phase considered which, above a certain current threshold, which is defined without great precision, commands or orders the speed limitation. Eventually, such a device may be situated within the grounded control, at the base of the circuit breaker, and in that case is controlled by the intensity transformer associated with the considered phase.

According to a modified embodiment of the present invention, the speed limitation is obtained with each operation, and intervenes between the distance d_0 for which the interruption of the capacitive current is terminated with certainty and the distance d_1 for which the interruption of short-circuit currents becomes possible; the speed limitation acts then also for the interruption of small inductive currents which is favorable, for a high speed might favor the current draw-out.

Additionally, the present invention has as its further object the provision of means intended to realize the high opening speed which constitutes one of the basic concepts of the present invention. According to a further feature of the present invention, the circuit breaker pole, i.e., the pole members belonging to the same phase, may be constituted in certain embodiments by placing in series interrupting chambers in which the speed of the rod is of the same order of magnitude as the speeds realized in conventional circuit breakers, and it will then comprise

a number of interrupting chambers which is clearly more considerable than that of the circuit breakers of analogous voltage with small oil-volume realized to date, and this is still another feature of the present invention.

FIGURE 5 illustrates a conventional arrangement of interrupting chambers connected in series, wherein 41, 42, 43 and 44 designate interrupting chambers similar to that of FIG. 3, the interrupting chamber being mounted on insulators 45 and 46 and actuated by hydraulic jacks 47 and 48.

According to still another feature of the present invention, the number of chambers in series is, in a modified embodiment of the present invention, of the same order as that encountered in certain conventional circuit breakers, and, the very considerable acceleration which then has to be imparted to the rod of each chamber to obtain, for the moment of separation of the contacts, the speed necessary for the interruption of capacitive currents, is obtained by the release of the pneumatic control energy; the opening of the circuit breaker by pneumatic energy with a view to attain a very high speed in the separation of the contacts, and associated, within a circuit breaker of small oil volume, with the anti-cavitation device mentioned hereinabove, constitutes also a feature of the invention.

As an illustrative embodiment, there may be used the hydropneumatic opening control, described in the French Patent No. 1,203,632, filed March 21, 1958, in the name of the assignee of the present application and in the three certificates of addition filed, respectively, on June 6, 1958, November 3, 1959, and February 19, 1960, for "Method of Hydro-Pneumatic Control for Electrical Apparatus and Application to a Circuit Breaker."

Neither the construction of a circuit breaker with a large number of interrupting chambers nor the opening control by means of pneumatic energy, however, will be described herein since any conventional known structure may be used therefor. The present text will be limited to the description, non-limitative in nature, of a cavitation compensating device according to the present invention, and to a circuit breaker equipped with such a device and provided with means, known per se, to assure to the opening the braking of the movable contact at an opportune time.

Referring now to the drawing wherein like reference numerals are used throughout the various views to designate corresponding parts, and more particularly to FIGURE 1, the tubular member 2 secured to a piston 3 slides along the axis of a cylindrical member 4. The piston 3 is displaced within the cylindrical member 4 in the lower part of which are arranged the fixed contacts 1 of any suitable construction of which only a single one is shown in the drawing. A spring 5 normally urges the piston member 3 downwardly as viewed in FIGURE 1, and thereby forces the oil located within the space 6 to pass through the throttling apertures 7 of any suitable cross section and inclined with respect to the axis of rod 2 so as to be divergent in the opening direction of rod 2. The lower guide portion 8 re-directs the oil towards the contacts 1 and toward the orifice of the spark arrester cover 9; as shown in cross section in FIGURE 2, the spark arrester cover comprises radial notches 10. This arrangement enables a reduction in the play between the cylindrical bore 11 of the cover 9 and the movable rod 12 which offers the advantage of avoiding the premature extinction of the arc which is the cause of re-ignitions and sometimes re-strikings before the movable rod 12 has left the cover 9 and to permit to bring up to speed the anti-cavitation compensating device from the beginning of the movement of the disengagement of the movable contact, by assuring to the oil a sufficient passage cross section by means of the notches 10.

OPERATION

The operation of the device illustrated in FIGURES 1 and 2 is as follows:

During closure of the circuit breaker, the compensating device is armed by the contact rod 12 which pushes the tubular member 2 and the piston 3 upwardly during that time and compresses thereby the spring 5 while penetrating into the fixed contact.

During the disengagement, a portion of the energy of the spring 5 is added to that of the conventional disengaging springs or of the hydro-pneumatic control of known construction to accelerate the rod 2 and the rod 12 at the beginning of the opening movement when a high speed is necessary; and the spring 5, pushing the piston 3, also forces the oil from space 6 through the apertures 7 against the guide 8 toward the extremity of the contact rod 12 thereby suppressing the cavitation and increasing the dielectric strength. The time of operation of the anti-cavitation device is controlled by the diaphragm or throttling apertures 7 in such a manner that the dielectric strength of the interruption distance attains approximately 2½ times the peak value of the simple voltage, a half period after the movable rod leaves the spark arrester cover 9 by eliminating the restrikings in case of capacitive interruptions. This forced flow of the oil ceases less than a half period later, and the interruption of inductive currents will take place, after this position, under the action of only the auto-blast, within the zone in which the dielectric strength of the interruption distance maintains substantially the value indicated hereinabove.

As soon as the anti-cavitation device ceases its effect, the movable contact may be braked very strongly and slowed down in order to reduce the energy released by the interruption of short-circuit currents, in the most unfavorable case, that is when a passage through zero accidentally arrives for an opening very slightly smaller than the minimum opening necessary for the interruption, which entrains the maintenance of the arc for a supplementary half period.

FIGURE 3 shows, in particular a braking device for the movable contact 12 which is operative by acting on the flow through an oil outlet or discharge line 20 connected to a cylinder containing the actuating piston 16 of which the piston rod is connected by the transmission linkage 15 to the movable contact rod 12 which is displaced within the interrupting chamber 13 contained within the insulating envelope 14 of the circuit breaker. As soon as the current attains a value at which it becomes desirable to slow down the movable part, the intensity of current traversing the circuit breaker which flows through the winding 17 and acts in opposition to the traction spring 19 normally seeking to bring back the magnetic core 18 to the left, displaces the latter toward the right, and the extremity 24 of the rod of piston 16, acting on the lever 25, tilts or rocks the lever 26 and displaces the check-value ball 27 by the intermediary of the movable valve stem and spool portion 28.

The oil coming from the input line 21 passes through line 29 and the orifice of the ball 27, and acting in opposition to springs 30 and 31, displaces the pistons 32 and 33 toward the right as viewed in FIGURE 3, the line 34 being connected to the tank or sump. The displaced oil, passing through line 20 is throttled by the channels 36 and 37 before reaching the return line 23. This reduction in the useful cross section of the oil discharge effectively brakes the movement of the piston 16. Thereafter, the lever 25 escapes from the free end 24 of the rod of the piston 16, whereupon the check valve 27 is displaced toward the left and cuts off the connection with the oil supply 21, 29. As a result thereof, the pistons 32 and 33 are displaced toward the left under the action of the springs 30 and 31 and re-establish the direct discharge communication between lines 20 and 23, thereby permitting anew a rapid movement of the movable contact toward the end of the path.

The operation of the valve 22 is regulated by conventional means in such a manner as to avoid any appreciable oscillatory movements of the movable part.

The present invention offers the following advantages:

(a) Elimination of the phenomenon of cavitation at the extremity of the movable contact which could be caused by the high speed of the latter, by displacing oil in the direction of displacement of the contact.

The combined action of high speed and over-pressure due to the blowing action eliminates the phenomena of cavitation as well as the formation of a conductive gas bubble producing restrikings in case of interruption of capacitive currents.

(b) There is avoided an appreciable elevation of the level of the voltage surges in the interruption of weak inductive currents by limiting the amplitude of the displacement of the oil by means of a throttling and by reducing the duration thereof to a time of the order of the period, while the interrupter is constructed in such a manner that the interruption of magnetizing currents then takes place some half-periods after the end of the displacement of the oil, under the action of the normal auto-blowing action of such apparatus which corresponds to the most favorable conditions of limiting voltage surges. The limitation of the duration presents, moreover, the advantage of decreasing the mechanical energy necessary to produce the blowing.

The device according to the present invention renders unnecessary the employment of damping resistances for the voltage surges since the interrupters with forced auto-blast cause, in the interruption of small inductive currents, only relatively small over-voltages or voltage surges.

(c) The eventual use of the hydro-pneumatic control permits to obtain, for a reduced price and volume, a large energy and therewith a high acceleration with a high speed of the movable contact and satisfactory damping.

(d) The initial high speed of the movable contact reduces the time necessary to attain the optimum interrupting position of inductive currents and consequently the interrupting times of all types of currents and the released energy.

(e) The eventual braking of the movable contact reduces the voltage of the arc, the released energy, the pressures developed within the interrupting members and consequently the cost of the construction of the extinguishing chamber.

(f) The interruption of the action of the spring within the anti-cavitation device before the slow down of the movable contact facilitates the latter operation and the braking in the course of the disengagement reduces considerably the importance of the damping necessary at the end of the path.

(g) The device utilized for the engagement permits to conserve a high speed of the movable contact during the existence of the arc at the closure and to introduce only toward the end of the path a resisting force which facilitates damping of the movable rod.

While we have shown and described one embodiment in accordance with the present invention, it is understood that the same is not limited thereto but is susceptible of many changes and modifications, and we therefore do not wish to be limited to the details shown and described herein but intend to cover all changes and modifications encompassed by the scope of the appended claims.

We claim:

1. A high-voltage, small-oil-volume circuit-breaker comprising stationary contact means having fixed contact fingers, movable contact means cooperating with said stationary contact means, housing means effectively forming an oil injection pot and including spark-arrester cover means, said movable contact means and the fixed contact fingers of said stationary contact means being disposed on the inside of said oil injection pot in the closing position thereof, and control means within said oil injection pot for controlling the opening movement of said movable contact means including means for aiding in imparting at the beginning of the opening movement a very high speed to said movable contact means and injecting

on said movable contact means an anti-cavitation oil current in the direction of movement of said movable contact means substantially free of swirling movements during substantially the entire duration of possible restriking 5 with capacitive interruptions.

2. A high-voltage, small-oil-volume circuit-breaker comprising stationary contact means having fixed contact fingers, movable contact means cooperating with said stationary contact means, housing means effectively forming

10 an oil injection pot and including spark-arrester cover means, said movable contact means and the fixed contact fingers of said stationary contact means being disposed on the inside of said oil injection pot in the closing position thereof, and control means within said oil injection pot for controlling the opening movement of said movable contact means including means for assisting in imparting at the beginning of the opening movement a very high speed to said movable contact means and means for injecting on said movable contact means an anti-cavitation 15 oil current substantially in the direction of movement of said movable contact means during substantially the entire duration of possible restriking with capacitive interruptions, said control means being regulated in such a manner that the maximum efficacy of said anti-cavitation 20 oil current commences less than a half-period after said movable contact means leaves said spark-arrested cover means and terminates at the maximum one period after said movable contact means leaves said cover means.

3. A high-voltage, small-oil-volume circuit-breaker comprising stationary contact means having fixed contact fingers, movable contact means cooperating with said stationary contact means, actuating means for effecting opening of said circuit breaker, housing means effectively forming an oil injection pot and including spark-arrester cover means, said movable contact means and the fixed contact fingers of said stationary contact means being disposed on the inside of said oil injection pot in the closing position thereof, and control means within said oil

30 injection pot for controlling the opening movement of said movable contact means including energy storage means armed during closure movement of said movable contact means, and means including said energy storage means assisted by the force produced by said actuating means for aiding in imparting at the beginning of the opening movement a very high speed to said movable contact means, and means for injecting on said movable contact means an anti-cavitation oil current substantially in the direction of movement of said movable contact means during the entire duration of possible restriking 35 with capacitive interruptions.

4. A high-voltage, small-oil-volume circuit-breaker comprising stationary contact means having fixed contact fingers, movable contact means cooperating with said stationary contact means, actuating means for effecting opening

40 of said circuit breaker, housing means effectively forming an oil injection pot and including spark-arrester cover means, said movable contact means and the fixed contact fingers of said stationary contact means being disposed on the inside of said oil injection pot in the closing position thereof, and control means within said oil injection

45 pot for controlling the opening movement of said movable contact means including energy storage means having disengaging spring means armed during closure movement of said movable contact means, and means including said energy storage means assisted by the force produced by said actuating means for aiding in imparting at the beginning of the opening movement a very high speed to said movable contact means, and means for injecting on said movable contact means an anti-cavitation oil current

50 substantially in the direction of opening movement of said movable contact means during the entire duration of possible restriking with capacitive interruptions.

5. A high-voltage, small-oil-volume circuit-breaker comprising stationary contact means having fixed contact fingers, movable contact means cooperating with said sta-

tionary contact means, actuating means including a hydro-pneumatic control system for effecting opening of said circuit breaker, housing means effectively forming an oil injection pot and including spark-arrester cover means, said movable contact means and the fixed contact fingers of said stationary contact means being disposed on the inside of said oil injection pot in the closing position thereof, and control means within said oil injection pot for controlling the opening movement of said movable contact means including energy storage means armed during closure movement of said movable contact means, and means including said energy storage means assisted by the force produced by said hydro-pneumatic control system of the actuating means for aiding in imparting at the beginning of the opening movement a very high speed to said movable contact means, and means for injecting on said movable contact means an anti-cavitation oil current substantially in the direction of opening movement of said movable contact means during the entire duration of possible restriking with capacitive interruptions.

6. A high-voltage, small-oil-volume circuit-breaker comprising stationary contact means having fixed contact fingers, movable contact means cooperating with said stationary contact means, housing means effectively forming an oil injection pot and including spark-arrester cover means, said movable contact means and the fixed contact fingers of said stationary contact means being disposed on the inside of said oil injection pot in the closure position thereof, and control means within said oil injection pot for controlling the opening movement of said movable contact means including means for aiding in imparting at the beginning of the opening movement a very high speed to said movable contact means and injecting on said movable contact means an anti-cavitation oil current in the direction of movement of said movable contact means substantially free of swirling movements during the entire duration of possible restriking with capacitive interruption, the interruption speed per pole structure being effectively multiplied by means producing a plurality of interrupting points placed in series.

7. A high-voltage circuit breaker provided with cooperating stationary and movable contact means, comprising means for imparting to said movable contact means a relatively very high opening velocity including braking means for subjecting said movable contact means to a braking action within a zone corresponding to substantially optimum position thereof for interrupting short-circuit currents and small inductive currents, and means injecting on said movable contact means an anti-cavitation oil current substantially in the direction of opening movement of said movable contact means and substantially during the entire duration of possible restriking with capacitive interruptions.

8. A high-voltage circuit breaker provided with cooperating stationary and movable contact means, comprising means for imparting to said movable contact means a relatively very high opening velocity including braking means for subjecting said movable contact means to a braking action within a zone corresponding to substantially optimum position thereof for interrupting short-circuit currents and small inductive currents, and means injecting on said movable contact means an anti-cavitation oil current substantially in the direction of opening movement of said movable contact means and substantially during the entire duration of possible restriking with capacitive interruptions, said braking means including a fluid-controlled system having valve means and electromagnetic actuating means for actuating said valve means in response to the current flowing through said circuit-breaker exceeding a predetermined threshold value to thereby control the flow of fluid medium within said fluid system.

9. A high-voltage circuit breaker provided with cooperating stationary and movable contact means, comprising means for imparting to said movable contact means

a relatively very high opening velocity including braking means for subjecting said movable contact means to a braking action within a zone corresponding to substantially optimum position thereof for interrupting short-circuit currents and small inductive currents, and means injecting on said movable contact means an anti-cavitation oil current substantially in the direction of opening movement of said movable contact means and substantially during the entire duration of possible restriking with capacitive interruptions, said braking means including a fluid-controlled system having valve means and electromagnetic actuating means for actuating said valve means in response to the current flowing through said circuit-breaker exceeding a predetermined threshold value to thereby control the flow of fluid medium within said fluid system, said braking means being operative by evacuation of said fluid medium.

10. A high-voltage circuit breaker provided, within a housing, with cooperating stationary and movable contact means, comprising means for imparting to said movable contact means a relatively very high opening velocity including braking means for subjecting said movable contact means to a braking action within a zone corresponding to substantially optimum position thereof for interrupting short-circuit currents and small inductive currents, and means within said housing injecting on said movable contact means an anti-cavitation oil current in the direction of opening movement of said movable contact means and substantially during only the entire duration of possible restriking with capacitive interruptions, said braking means including a fluid-controlled system having valve means and electromagnetic actuating means for actuating said valve means in response to the current flowing through said circuit breaker exceeding a predetermined threshold value to thereby control the flow of fluid medium within said fluid system, said braking means being operative by admission of said fluid medium.

11. A high-voltage, small-oil-volume circuit-breaker comprising stationary contact means having fixed contact fingers, movable contact means cooperating with said stationary contact means, housing means effectively forming an oil injection pot and including spark-arrester cover means, said movable contact means and the fixed contact fingers of said stationary contact means being disposed on the inside of said oil injection pot in the closure position thereof, and control means within said oil injection pot for controlling the opening movement of said movable contact means including energy storage means armed during closure movement of said movable contact means, means including said energy storage means for aiding in imparting at the beginning of the opening movement a very high speed to said movable contact means, and means injecting on said movable contact means an anti-cavitation oil current substantially in the direction of opening movement of said movable contact means and during the entire duration of possible restriking with capacitive interruptions including partition wall means forming throttling aperture means for the oil and effectively interposed between said energy storage means and said spark-arrester cover means.

12. A high-voltage, small-oil-volume circuit-breaker comprising stationary contact means, movable contact means cooperating with said stationary contact means and including a contact rod, housing means effectively forming an oil injection pot and including spark-arrester cover means, said movable contact means and said stationary contact means being disposed on the inside of said oil injection pot in the closure position thereof, and control means within said oil injection pot for controlling the opening movement of said movable contact means including energy storage means armed during closure movement of said movable contact means and having cylinder means slidably accommodating therein piston means having a piston rod pushed back by said contact rod during closing movement thereof to compress spring means,

means including said energy storage means for assisting in imparting at the beginning of the opening movement a very high speed to said movable contact means, and means including said piston means for injecting on said movable contact means an anti-cavitation oil current substantially in the direction of opening movement of said movable contact means and substantially only during the entire duration of possible restriking with capacitive interruptions.

13. A high-voltage, small-oil-volume circuit-breaker comprising stationary contact means having fixed contact fingers, movable contact means cooperating with said stationary contact including a contact rod, housing means effectively forming an oil injection pot and including spark-arrester cover means, said movable contact means and the fixed contact fingers of said stationary contact means being disposed on the inside of said oil injection pot in the closure position thereof, and control means within said oil injection pot for controlling the opening movement of said movable contact means including energy storage means armed during closure movement of said movable contact means, means including said energy storage means for aiding in imparting at the beginning of the opening movement a very high speed to said movable contact means, and means injecting on said movable contact means an anti-cavitation oil current substantially in the direction of movement of said movable contact means during the entire duration of possible restriking with capacitive interruptions including partition wall means forming throttling aperture means for the oil and effectively interposed between said energy storage means and said spark-arrester cover means, said spark-arrester cover means being provided with a central bore for the passage therethrough, with reduced play, of said contact rod and with perforations for the passage of oil.

14. A high-voltage, small-oil-volume circuit-breaker comprising stationary contact means having fixed contact fingers, movable contact means cooperating with said stationary contact means including a contact rod, housing means effectively forming an oil injection pot and including spark-arrester cover means, said movable contact means and the fixed contact fingers of said stationary contact means being disposed on the inside of said oil injection pot in the closure position thereof, and control means within said oil injection pot for controlling the opening movement of said movable contact means including energy storage means armed during closure movement of said movable contact means, means including said energy storage means for aiding in imparting at the beginning of the opening movement a very high speed to said movable contact means, and means injecting on said movable contact means an anti-cavitation oil current substantially in the direction of movement of said movable contact means during the entire duration of possible restriking with capacitive interruptions including partition wall means forming throttling aperture means for the oil and effectively interposed between said energy storage means and said spark-arrester cover means, said spark-arrester cover means being provided with a central bore for the passage therethrough, with reduced play, of said contact rod and with perforations for the passage of oil, said perforations being in the form of radial channels extending substantially radially outwardly from said central bore.

15. A high-voltage, small-oil-volume circuit-breaker comprising stationary contact means having fixed contact fingers, movable contact means cooperating with said stationary contact means including a contact rod, housing means effectively forming an oil injection pot and including spark-arrester cover means, said movable contact means and the fixed contact fingers of said stationary contact means being disposed on the inside of said oil injection pot in the closure position thereof, and control means within said oil injection pot for controlling the opening movement of said movable contact means including en-

ergy storage means armed during closure movement of said movable contact means, means including said energy storage means for aiding in imparting at the beginning of the opening movement a very high speed to said movable contact means, and means injecting on said movable contact means an anti-cavitation oil current substantially in the direction of movement of said movable contact means during the entire duration of possible restriking with capacitive interruptions including partition wall means forming throttling aperture means for the oil having a divergent direction in the opening sense of said movable contact means and effectively interposed between said energy storage means and said spark-arrester cover means, said spark-arrester cover means being provided with a central bore for the passage therethrough, with reduced play, of said contact rod and with perforations for the passage of oil, said perforations being in the form of radial channels extending substantially radially outwardly from said central bore.

20 16. A high-voltage, small-oil-volume circuit-breaker comprising stationary contact means, movable contact means cooperating with said stationary contact means and including a contact rod, housing means effectively forming an oil injection pot and including spark-arrester cover means, said movable contact means and said stationary contact means being disposed on the inside of said oil injection pot in the closure position thereof, and control means within said oil injection pot for controlling the opening movement of said movable contact means including energy storage means armed during closure movement of said movable contact means and having cylinder means slidably accommodating therein piston means having a piston rod pushed back by said contact rod during closing movement thereof to compress spring means, means including said energy storage means for aiding in imparting at the beginning of the opening movement a very high speed to said movable contact means, brake means for subjecting said movable contact means to a braking action in the opening movement thereof in a position of said movable contact means corresponding substantially to optimum position for interrupting short-circuit currents and small inductive currents, and means including said piston means for injecting on said movable contact means an anti-cavitation oil current substantially in the direction of displacement of said movable contact means during the entire duration of possible restriking with capacitive interruptions including throttling means for the oil intermediate the cylinder means of said energy storage means and said spark-arrester cover means, said spark-arrester cover means being provided with perforations for the passage of oil and said contact rod extending through said cover means with a relatively reduced clearance, said perforations being in the form of radial notches extending radially outwardly from the central aperture provided for the passage of said contact rod.

25 17. A high-voltage, small-oil-volume circuit-breaker comprising stationary contact means, movable contact means cooperating with said stationary contact means and including a contact rod, housing means effectively forming an oil injection pot and including spark-arrester cover means, said movable contact means and said stationary contact means being disposed on the inside of said oil injection pot in the closure position thereof, and control means within said oil injection pot for controlling the opening movement of said movable contact means including energy storage means armed during closure movement of said movable contact means and having cylinder means slidably accommodating therein piston means having a piston rod pushed back by said contact rod during closing movement thereof to compress spring means, means including said energy storage means for assisting in imparting at the beginning of the opening movement a very high speed to said movable contact means, brake means for subjecting said movable contact means to a braking action in the opening movement thereof in a position of said

movable contact means corresponding substantially to optimum position for interrupting short-circuit currents and small inductive currents, and means including said piston means for injecting on said movable contact means an anti-cavitation oil current substantially in the direction of displacement of said movable contact means during the entire duration of possible restriking with capacitive interruptions including throttling means for the oil effectively diverging in the opening direction of said movable contact means and disposed intermediate the cylinder means of said energy storage means and said spark-arrester cover means, said spark-arrester cover means being provided with perforations for the passage of oil and said contact rod extending through said cover means with a relatively reduced clearance, said perforations being in the form of radial notches extending radially outwardly from the central aperture provided for the passage of said contact rod.

18. A high-voltage, small-oil-volume circuit-breaker comprising stationary contact means, movable contact means cooperating with said stationary contact means, housing means effectively forming an oil injection pot and including spark-arrester cover means, said movable contact means and said stationary contact means being disposed on the inside of said oil injection pot in the closure position thereof, and control means within said oil injection pot for controlling the opening movement of said movable contact means including energy storage means armed during closure movement of said movable contact means, means including said energy storage means for aiding in imparting at the beginning of the opening movement a very high speed to said movable contact means, and means injecting on said movable contact means an anticavitation oil current approximately in the direction of displacement of said movable contact means and substantially during the entire duration of possible restriking with capacitive interruptions including cylinder means for the oil, piston means in said cylinder means having a piston rod with a base, throttling means for the oil effectively formed between said energy storage means and said spark-arrester cover means, said throttling means being provided with aperture means having effectively a divergence in the direction of opening movement of said movable contact means, and said injection being effected also by said piston which is provided with orifices establishing a communication for said base with said cylinder means.

19. A high-voltage, small-oil-volume circuit-breaker comprising stationary contact means, movable contact means cooperating with said stationary contact means, housing means effectively forming an oil injection pot and including spark-arrester cover means, said movable contact means and said stationary contact means being disposed on the inside of said oil injection pot in the closure position thereof, and control means within said oil injection pot for controlling the opening movement of said movable contact means including energy storage means armed during closure movement of said movable contact means, means including said energy storage means for aiding in imparting at the beginning of the opening movement a very high speed to said movable contact means, and means injecting on said movable contact means an anti-cavitation oil current approximately in the direction of displacement of said movable contact means and substantially during the entire duration of possible restriking with capacitive interruptions including partition wall means intermediate said energy storage means and said spark-arrester cover means forming a perforated diaphragm for the oil, said partition wall means being axially extended in the direction of closing movement of said movable contact means by a tubular portion in which stops the head portion of said movable contact means in the closure position thereof.

20. A high-voltage, small-oil-volume circuit-breaker

comprising stationary contact means, movable contact means cooperating with said stationary contact means, housing means effectively forming an oil injection pot and including spark-arrester cover means, said movable contact means and said stationary contact means being disposed on the inside of said oil injection pot in the closure position thereof, and control means within said oil injection pot for controlling the opening movement of said movable contact means including energy storage means armed during closure movement of said movable contact means, means including said energy storage means for assisting in imparting at the beginning of the opening movement a very high speed to said movable contact means, hydraulically actuated means for subjecting said movable contact means to braking action in the opening movement thereof in a position of said movable contact means corresponding substantially to optimum position for interrupting short-circuit currents and small inductive currents, and means injecting on said movable contact means an anti-cavitation oil current approximately in the direction of displacement of said movable contact means and substantially during the entire duration of possible restriking with capacitive interruptions including cylinder means for the oil, piston means in said cylinder means having a piston rod with a base, throttling means for the oil effectively formed between said energy storage means and said spark-arrester cover means, said throttling means being provided with aperture means having effectively a divergence in the direction of opening movement of said movable contact means, and said injection being effected also by said piston which is provided with orifices establishing a communication for said base with said cylinder means.

21. A high-voltage, small-oil-volume circuit-breaker comprising stationary contact means having fixed contact fingers, movable contact means cooperating with said stationary contact means, housing means effectively forming an oil injection pot and including spark-arrester cover means, said movable contact means and the fixed contact fingers of said stationary contact means being disposed on the inside of said oil injection pot in the closure position thereof, said oil injection pot having a reduced diameter in the portion thereof directly adjoining said spark-arrester cover means and said fixed contact fingers being disposed in said last-mentioned portion, and control means within said oil injection pot for controlling the opening movement of said movable contact means including energy storage means armed during closure movement of said movable contact means, means including said energy storage means for aiding in imparting at the beginning of the opening movement a very high speed to said movable contact means, and means injecting on said movable contact means an anti-cavitation oil current substantially in the direction of displacement of said movable contact means during the entire duration of possible restriking with capacitive interruptions including throttling aperture means for the oil intermediate said energy storage means and said spark-arrester cover means.
